UNITED STATES PATENT OFFICE.

RICHARD H. CUTLER, OF RICHLAND, IOWA, ASSIGNOR OF ONE-HALF TO
F. M. SWEARINGEN, OF SAME PLACE.

END-GATE AND SCOOP-BOARD FOR WAGONS.

SPECIFICATION forming part of Letters Patent No. 242,514, dated June 7, 1881.

Application filed March 30, 1881. (Model.)

To all whom it may concern:

Be it known that I, RICHARD H. CUTLER, of Richland, in the county of Keokuk and State of Iowa, have invented certain new and useful Improvements in End-Gates and Scoop-Boards for Wagons; and I do hereby declare that the following is a full, clear, and exact description of the invention, which will enable others skilled in the art to which it appertains to make and use the same, reference being had to the accompanying drawings, which form a part of this specification.

My invention relates to end-gates and scoop-boards for wagons; and it consists in the construction and arrangement of parts, as herein-after more fully described and claimed.

In the annexed drawings, Figure 1 is a perspective view of wagon with end-gate open. Fig. 2 is a side view with end-gate closed, and Fig. 3 is an end view of the same.

Like letters indicate like parts.

A represents a combined end-gate and scoop-board, that is attached by T-hinges to the wagon-body A', and rests, when fully let down, on the ledge a. On each side of the end-gate is a segmental side piece, a', to the edge of which is secured a metal rim, that terminates at its forward end in a spring-pawl, B, which engages with a segmental toothed bar or rack, C, on the side of the wagon. The spring-pawls B are operated by a lever, b, on the outer side of each side piece, a', and, by means of handles b' b', may be disengaged from the racks C C when it is desired to let down or open the end-gate.

Risers D D are removably attached on each

side of the wagon, and a similar riser, E, is also attached in like manner to the upper part of the end-gate, where it may be secured, if desired, by a hook, e, and staple d. The riser 40 E is provided on each side with a lug or clasp, e, that fits on the outer side of the riser D when the end-gate is closed. A hooked clasp, f, is formed at the upper end of the rack C, and is turned down over the side pieces, a' a'. 45

It will be seen that the end-gate may be readily operated by means of the levers b b, so as to bring the pawls B B into engagement with the toothed under surface of the racks C C at such points as to suspend the gate at any 50 desired angle, thus, in connection with the risers D D and E, greatly increasing the capacity of the wagon.

The devices constructed as above described are simple, convenient, and effective, and are 55 not liable to get out of order.

Having thus described my invention, what I claim as new, and desire to secure by Letters Patent, is—

The combination, with the wagon-body A', 60 having notched segmental bars C, of the end-gate A, having curved side pieces, a', provided with spring-metal rims having pawls B, and the levers or rods b and handles b', as herein described, for the purpose shown and specified. 65

In testimony that I claim the foregoing as my own I have hereto affixed my signature in presence of two witnesses.

RICHARD HENRY CUTLER.
